HARMONICA TESTER

Charles Trevor, Jersey City, N. J.

Application April 3, 1937, Serial No. 134,761

3 Claims. (Cl. 84—377)

This invention relates to new and useful improvements in a harmonica tester.

More specifically, this invention contemplates the provision of a mouthpiece which may be used in connection with a harmonica to test the reeds thereof. The use of one's mouth for testing harmonicas in factories has proved very unsanitary and has been outlawed in a number of states.

10. Further, if one continually blows upon a harmonica the edge portions thereof tend to scrape and irritate the lips of the person doing the blowing with the result that unsightly sores develop.

15. The invention is further characterized by a mouthpiece which is adapted to be resiliently engaged over the front edge of a harmonica for maintaining the harmonica in position and for permitting it to be adjusted across the front thereof.

20. The invention is further characterized by a bulb constructed of soft rubber or similar material which is attached to the back of the mouthpiece and which may be compressed to force air through the mouthpiece to sound and so test the harmonica.

25. Still further the invention is characterized by a mouthpiece having a construction which permits it to be easily engaged and removed from the harmonica to enhance the testing qualities thereof.

30. Another characteristic of the invention is the provision of an adjustable means associated with the mouthpiece of the device which may be used in conjunction with a harmonica having a double row of reeds to selectively test either the upper or lower row of reeds.

35. Still further the means for selectively testing the upper and lower row of reeds provides superimposed openings in the mouthpiece which are alignable with the superimposed openings in the front edge of the harmonica and a disc member rotative in said mouthpiece and having a pair of openings at right angles to each other adapted to be selectively engaged with either of the openings in the mouthpiece to permit the air to pass through the reeds.

40. For further comprehension of the invention, and of the objects and advantages thereof, reference will be had to the following description and accompanying drawing, and to the appended claims in which the various novel features of the invention are more particularly set forth.

45. In the accompanying drawing forming a material part of this disclosure:—

Fig. 1 is a perspective view of the device engaged on a harmonica with a portion thereof broken away to reveal interior construction.

Fig. 2 is a perspective view of the harmonica tester, per se.

Fig. 3 is an enlarged sectional detailed view of a portion of Fig. 2.

Fig. 4 is a sectional view taken on the line 4—4 of Fig. 3.

5. The harmonica tester, according to this invention, includes a mouthpiece 11 which is adapted to be engaged over the front edge of a harmonica 12 and resiliently maintain its position thereon and also capable of manual movement along the harmonica 12. A bulb 10 is mounted on 10 said mouthpiece for forcing air through said mouthpiece to sound and so test the harmonica.

15. The mouthpiece 11 comprises a lip portion 11a and a rear portion 11b pivotally connected together by means of a pintle pin 13 forming an 20 axis therefor. The lip portion 11a has a circular disc element 14 fixedly mounted thereon by means of rivets 15. The rear portion 11b has a section 11c to which a plate 16 is fixedly attached by means of rivets 17. The section 11c is vulcanized, cemented, or in any other manner fixedly attached to an element 11d forming the completed back portion 11b.

25. The harmonica 12 has superimposed openings 18 which lead to a double row of reeds contained 30 within the harmonica 12. The lip portion 11a of the mouthpiece 11 engages over the sides 12a of the harmonica and has resilient flanges 19 fixedly attached at one of their ends to said lip portion and frictionally engaging the sides of 35 the harmonica to maintain the lip portion 11a in position thereon and permit it to be manually moved along the front edge of the harmonica. These flange portions 19 are vulcanized, cemented, or in any other manner attached to the lip 40 portion 11a.

45. The lip portion 11a has a pair of openings 20 angularly spaced 180° relative to the axis of the pintle 13 which are alignable with the passages 18 in the front edge of the harmonica to 45 permit the air to pass therethrough to the reeds. The rear portion 11b has a pair of passages 21 (see Fig. 4) angularly spaced 90° relative to the axis of the pintle pin 13 which are selectively alignable with the passages 20 when the bulb 50 portion 10 is rotated through 90° to permit the air to be selectively passed through the upper or lower passages 18 to sound either the upper or lower set of reeds.

55. The back section 11d has a screen 22 mounted 55

therein to stiffen this section and help it to maintain its normal shape to prevent buckling between the disc element 14 and the plate 16 to prevent rotation thereof. This section 11^a is also 5 fixedly connected with the bulb 10 which is constructed of a relatively soft rubber material which is easily compressed to force air through the passages 20 and 21 within the mouthpiece 11 of the harmonica tester and through to the passages 18 in the harmonica 12.

10 A means is provided on the disc 14 which engages the plate 16 to limit the distance through which these elements may be rotated to 90°. This means includes a pin 25 extending from the disc 14 and engaging in a 90° slot 26 angularly formed 180° from the openings 21 in the rear section 11^b. Thus the bulb 10 may be turned through 90° to complete a passage through the upper opening 20 or through the lower opening 21 (see Fig. 3).

15 20 The operation of the device is as follows:—

Assuming that the position of the elements shown in Fig. 3 is their normal position and the bulb 10 is compressed, the air contained therein will pass through the screen 22, the opening 25 21, the top opening 20 in the lip portion 11^a which is aligned with the top openings 18 in the harmonica 12 which permits the air to freely pass to the reeds within the top passage 18 to sound and so test the harmonica.

30 35 If it is desired to test the lower reeds of the harmonica the harmonica is held rigid in one hand while the bulb 10 is rotated through 90° by the other hand. When the bulb 10 is now compressed the air will pass through the opening 40 21 (see Fig. 4), which is now aligned with the lower passages 20 (see Fig. 3) to permit the air to pass through the lower passage 18 to pass over the lower reeds within the harmonica 12 to test these reeds. Thus it may be seen that by a simple twist of one's wrist, while the other is maintained rigid, the device may be adjusted to easily 45 50 test the upper or lower reeds of the harmonica 12. The flange members 19 which engage the sides of the harmonica 12 resiliently maintain the lip portion 11^a on the edge of the harmonica 12 and at the same time act as a seal to prevent the compressed air from passing between the sides of the harmonica 12 and the lip portion 11^a.

55 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In combination with a harmonica having a 60 double row of reeds, a harmonica tester comprising a mouthpiece having a pair of superimposed openings alignable with the passages to said reeds and being adapted to engage over the front edge of a harmonica and a bulb mounted 65 on said mouthpiece for forcing the air through

said mouthpiece to sound and so test said harmonica, and means on said mouthpiece for selectively testing the upper or lower reeds of said harmonica when said bulb is compressed, said means comprising said mouthpiece having a 5 front and rear section rotatively connected together, a disc element fixedly mounted on said front section and having superimposed openings alignable with said openings, a plate element having a pair of openings at right angles to each other and selectively alignable with the superimposed openings in said disc element to permit the air to be forced through to either the top or bottom row of reeds.

2. In combination with a harmonica having a 15 double row of reeds, a harmonica tester comprising a mouthpiece having a pair of superimposed openings alignable with the passages to said reeds and being adapted to engage over the front edge of a harmonica and a bulb mounted 20 on said mouthpiece for forcing the air through said mouthpiece to sound and so test said harmonica, and means on said mouthpiece for selectively testing the upper or lower reeds of said harmonica when said bulb is compressed, said means comprising said mouthpiece having a front 25 and rear section rotatively connected together, a disc element fixedly mounted on said front section and having superimposed openings alignable with said openings, a plate element having a pair 30 of openings at right angles to each other and selectively alignable with the superimposed openings in said disc element to permit the air to be forced through to either the top or bottom row of reeds, said rotative connection comprising a 35 pin rotatively connecting together said disc element and said plate element.

3. In combination with a harmonica having a 40 double row of reeds, a harmonica tester comprising a mouthpiece having a pair of superimposed 45 openings alignable with the passages to said reeds and being adapted to engage over the front edge of a harmonica and a bulb mounted on said mouthpiece for forcing the air through said mouthpiece to sound and so test said harmonica, 50 and means on said mouthpiece for selectively testing the upper or lower reeds of said harmonica when said bulb is compressed, said means comprising said mouthpiece having a front and rear section rotatively connected together, a disc element fixedly mounted on said front section and having superimposed openings alignable with said openings, a plate element having a pair 55 of openings at right angles to each other and selectively alignable with the superimposed openings in said disc element to permit air to be forced through to either the top or bottom row of reeds, and a screen mounted just in back of the openings in the rear section of said mouthpiece to reinforce said mouthpiece and prevent the sections thereof from buckling and so hinder rotation of the sections when the bulb is compressed.

CHARLES TREVOR. 65
